(57) **CLAIM**

The ornamental design for a suitcase, as shown and described.

DESCRIPTION

FIG. 1 is a front perspective view of a suitcase showing my new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is an enlarged view of the area within the broken line rectangle identified by reference numeral 9 in FIG. 8;

FIG. 10 is a front perspective view of the suitcase of FIGS.

1-9 with the handle shown in an extended position; and,

FIG. 11 is a rear perspective view of the suitcase of FIGS.

1-9 with the handle shown in an extended position.

The dot-dash broken lines at the bottom of the handles on the top and side of the suitcase represent boundary lines and form no part of the claimed design. The even-length dash broken line rectangle labeled by numeral 9 in FIG. 8, and the even-length dash broken line rectangle surrounding the enlarged region in FIG. 9, define the bounds of the enlargement and form no part of the claimed design. The even-length dash broken lines depicting the remaining portions of the suitcase form no part of the claimed design.
